CLAIM

The ornamental design for a vaporizer device with surface ornamentation, as shown and described.

DESCRIPTION

FIG. 1 is a front right top perspective view of a vaporizer device showing my new design;

FIG. 2 is a back right top perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof;

FIG. 8 is an opposite side view thereof;

FIG. 9 is a back left top perspective view thereof;

FIG. 10 is a front left top perspective view thereof;

FIG. 11 is a front right bottom perspective view thereof;

FIG. 12 is a back right bottom perspective view thereof;

FIG. 13 is a back left bottom perspective view thereof; and,

FIG. 14 is a front left bottom perspective view thereof.

In FIGS. 1, 3, 7-8, 10-11, and 14, the array of circles is a surface ornamentation applied to the vaporizer device.

In the drawings, the broken lines represents boundaries and forms no part of the claim.

1 Claim, 6 Drawing Sheets
